FIG. 1.

FIG. 2.

Inventor:
Edwin R. Barney,
by Franklin E. Low.

accy.

UNITED STATES PATENT OFFICE

2,195,442

RECEPTACLE

Edwin R. Barney, Newton, Mass.

Application June 15, 1937, Serial No. 148,253

3 Claims. (Cl. 229—1.5)

This invention relates to a receptacle, and has for its object to provide an inexpensive article of the character mentioned and preferably adapted to serve as a tray and embodying therein a flange or rim portion provided with a central opening therein which may be formed as a depression in the rim adapted to receive a main order of food, as, for example, fried clams, oysters, scallops, potatoes, ice cream, etc., or, said opening may be formed as a hole in which a separate receptacle containing the foods above mentioned may be inserted and held while said foods are being consumed; said rim also having other small depressed portions and openings provided therein adapted to receive small quantities of seasoning materials and relishes together with service equipment and eating utensils, as, for example, paper napkins and small paper or wood spoons and forks and the like which may be inserted in the openings for the convenience and use of the persons using the receptacle and consuming the food.

The invention consists in a receptacle as set forth in the following specification and particularly as pointed out in the claims.

Referring to the drawing:

Fig. 1 is a perspective view of a receptacle embodying my invention.

Fig. 2 is a perspective view of another receptacle embodying my invention.

In the drawing, referring particularly to Fig. 1, 5 represents a receptacle, constituting a tray, preferably rectangular in form and constructed of pressed or moulded paper or pasteboard or any other suitable paper stock. The material is treated in any suitable manner to render it waterproof and also greaseproof. The receptacle 5 embodies therein a flat horizontal flange or rim portion 6 having a central opening 7 therein preferably formed as a depression in said rim in which a main order of food, as, for example, fried clams, oysters, scallops, potatoes, ice cream, and similar foods served at roadside stands may be placed to be eaten directly from the receptacle out of doors where the usual conveniences are missing.

In serving the above-mentioned foods under the conditions mentioned, it is also desirable to provide the purchaser of the foods with small quantities of certain types of relishes and seasoning materials, and also certain types of inexpensive eating utensils as, for example, paper or wood spoons and forks. The rim 6 is, therefore, provided with depressions 8 and 9 pressed therein, the depression 8 being comparatively shallow and the depression 9 being relatively deeper, and

these depressions may be utilized for the reception of solid or liquid seasoning materials and relishes or other materials, as may be desired. The rim 6 is also provided with a circular opening 10 and a slot 11 extending therethrough, in either of which eating utensils such as paper or wood spoons and forks, or paper napkins, may be inserted. Small paper cups, well known in the art, and used extensively in serving small orders of liquids as, for example, cream or milk for use in hot beverages, and for relishes and sauces served with meats, fish and the like, may be inserted loosely in the depressions 8 and 9, or in the opening 10.

The receptacle of this invention forms a convenient and inexpensive means for holding foods and seasoning materials therefor served at roadside stands to be eaten out of doors, as at picnics, or in automobiles, where the usual conveniences are lacking, the main order of food being located within the main depression 1, the seasoning materials and relishes within the small depressions 8 and 9, and the eating utensils within the circular opening 10 and slot 11; and it is evident that other depressions and openings of various shapes and sizes may be provided in the rim 6 as may be desired.

In Fig. 2 I have illustrated another embodiment of my invention in which a rectangular tray 12 embodying therein a flat horizontal rim is provided with a central opening 13 formed as a hole in said rim in which another paper receptacle 14, well known in the art, and illustrated in light dash lines, may be inserted with the top of said receptacle protruding a short distance above the top of the tray. The tray 12 is preferably constructed of pressed or moulded waterproofed and greaseproofed paper or paper stock, and is provided with depressions 15 and 16 of different depths, a circular opening 17, and a slot 18, all of which are formed in the same manner and for the same purpose as the depressions and openings previously mentioned in connection with the disclosure of Fig. 1. In this embodiment of the invention the main order of food is served in the receptacle 14, and the tray 12 is utilized to hold the seasoning materials and eating utensils. The cover flaps forming a part of the receptacle 14 are folded outwardly as may be found necessary or desirable while the food is being consumed.

Although I have illustrated the tray portions of both embodiments of this invention as being rectangular in form, it is evident that said trays and the various depressions and openings therein may be circular in form, or any other form, if it

is so desired and, furthermore, the receptacles may be constructed of other well known materials as, for example, sheet metal, cast metal, or earthenware, without departing from the spirit of the 5 invention.

I claim:

1. A receptacle for foods formed of a single piece of material and having a flat portion embodied therein provided with a relatively large 10 main opening therein arranged to receive a container for food, said flat portion also being provided with relatively small depressions of different depths for the reception of foods, and with holes of diversified shapes extending entirely 15 therethrough in which eating utensils and napkins may be inserted to rest thereon.

2. A receptacle for foods formed of a single piece of paper stock and having a flat portion provided with a relatively large main depression

therein for the reception of foods, said flat portion also being provided with other relatively small depressions therein for the reception of foods, and with a slot and another opening extending entirely therethrough in which eating utensils and 5 napkins may be inserted to be supported thereby.

3. A receptacle for foods formed of a single piece of pressed paper stock and having a flat rectangular portion provided with a relatively large main depression therein adapted to receive 10 a main order of food, said flat portion also being provided with other relatively small depressions at one end thereof adapted to receive small orders of food and with a slot and another opening extending entirely therethrough at the other end 15 thereof in which eating utensils, napkins and the like may be inserted.

EDWIN R. BARNEY.
